FIRE DOOR

Jean Hollender, Bogota, N. J., assignor to Franklin Railway Supply Company, New York, N. Y., a corporation of Delaware

Application September 16, 1931, Serial No. 563,044

10 Claims. (Cl. 110—176)

This invention relates to fire doors, and especially to doors for locomotive fire boxes.

An important object of the invention is to provide a door which will afford the engineer and fireman the maximum of protection in case of accident or structural failure resulting in discharge of steam inside the firebox,—even in the case of high pressure locomotives using boiler pressures as great as 400 lbs. per sq. in. or over. 10 Other objects and advantages that can be realized through the invention will appear from my description hereinafter of a preferred embodiment.

In the drawings:

15 Fig. 1 shows a vertical section through a firebox door opening equipped with one form of door conveniently embodying my invention, taken as indicated by the line and arrows 1—1 in Fig. 2.

20 Fig. 2 is a front view of the door and its associated parts and operating mechanism, from outside the firebox.

Fig. 3 is a side elevation of the parts outside the firebox, from the left of Fig. 2.

25 Fig. 4 shows a vertical section through certain parts of the operating mechanism, taken as indicated by the line and arrows 4—4 in Fig. 2.

In Figs. 1 and 2 is shown a fire-box water-wall 5 with a door opening or doorway of rectangular, 30 round-cornered outline into which the door frame is adapted to fit. In the present instance, the door to be described is shown as being applied to a stoker fired locomotive, the stoker discharge tube 4 being illustrated as occupying the lower portion of the opening in the water wall. 35 The invention, however, is not to be limited to this type of construction because my improved door could be designed for use independently of a stoker.

40 The door frame comprises a part or section 6 mounted directly in the door opening of the firebox, and affording a seat-shoulder 7 for the door 8, and also, in the present instance, an outside part or section 9 mounted against the firebox wall 5 around the outward projecting flange or margin 11 of the part 6, and secured to the latter by bolts 12. The seat-shoulder 7 directly sustains the door 8 against pressure inside the firebox.

45 The frame section 6 that includes this door-seat 7 also has a flange or shoulder 13 that abuts against the inside of the firebox 5 around the door opening and (assisted by the inward and downward flare of the frame 6 at its lower side) sustains the frame against outward pressure on the

door. Thus the stud bolts 14 (around the door opening) that secure the outer frame section 9 need only be numerous and strong enough to hold and support it firmly under the stresses imposed by the parts and mechanism mounted on it, since they do not have to withstand the outward pressure on the door in case of rupture of the inside firebox wall. 5

The inside frame or section 6 can readily be installed by inserting it endwise through the firebox doorway, then turning it parallel with the wall 5, and working it back into the doorway to the position shown in Fig. 1. This can be done after the outside frame or section 9 has been secured in place by the stud-bolts 14. The two 10 sections are fastened together by the bolts 12, and the inner section thus securely held and definitely fixed in position. 15

As here shown, the outer frame 9 preferably carries the door-operating mechanism, including a shaft 15 mounted in bearing lugs 16, 16 on the frame 9. This shaft 15 is operable either manually or by fluid pressure, and is suitably connected to the door 8. As shown, however, the door 8 itself is not (preferably) supported by the shaft 15, but from the inner frame 6. For this purpose (Figs. 1 and 2), the door 8 has hinge-lugs 17, which are accommodated in recesses in the frame 6 and pivoted on pins 18 removably mounted in bosses or enlargements 19 at the sides of the frame. The shaft 15 has crank arms 20, 20 fixed thereon which are connected by links 21, 21 to ears or lugs 22, 22 on the door 8, so that when the shaft 15 is turned something less than 90° counterclockwise (Fig. 1), the door is 25 swung open inward as shown in dotted lines. When, on the other hand, the opening force applied to the shaft 15 is released, the door 8 closes automatically, of its own weight. Any pressure 30 or explosive force acting on the door 8 from inside the furnace 5 also tends to close it. 35

40 For manually operating the door 8, there is a hand lever 25 mounted in a collar-block 26 on the shaft 15. A pull outward and downward on the 45 lever 25 (Fig. 3) turns the shaft 15 counter-clockwise (Fig. 1) and opens the door 8. As shown in Fig. 2, the hand lever 25 is pivoted to the block 26 at 27, so that the lever can be swung to the left from the vertical and engaged in a notch or 50 fork 28 on an upward extension of one of the shaft bearing lugs 16, thus locking the parts in position. The block 26 is not fixed on the shaft 15; however, but, on the contrary, is yieldingly 55 connected to the shaft, by a crown tooth clutch

- arrangement consisting of a longitudinally shiftable collar 30 on the shaft whose bevelled teeth 31 are yieldingly pressed into engagement in bevelled notches in the collar block 26 by a helical compression spring 33, acting between the collar 30 and an abutment collar 34 fixed on the shaft. The spring 33 is strong enough to hold the clutch engaged for normal operation of the door 8 by the hand lever 25, but yields and allows the clutch 5 to disengage when any closing force materially greater than the weight of the door 8 is brought to bear, thus allowing the door to close at once under pressure in the firebox, regardless of the position of the hand lever 25.
- 10 For power operation of the door 8, there is a fluid motor comprising a cylinder 35 mounted on the frame 9, with a piston 36 connected by a link 37 to a crank arm 38 fast on the shaft 15. Pressure fluid may be admitted to the cylinder 35 15 above the piston 36, or exhausted therefrom, to open the door 8 or allow it to close, through a pipe 39 controlled by a suitable foot-operated valve device 40, such as commonly used for controlling the operation of furnace doors. A pipe 20 41 is shown connected to the valve device 40 for supplying pressure fluid from any suitable source,—such as the compressed air reservoir (not shown) of an air brake system.
- To permit door-opening operation of the shaft 30 15 by the piston 36 even when the hand lever is locked in "door closed" position, a lost-motion connection may be provided between the shaft 15 and the clutch collar 30. For this purpose, there 35 is a key 43 projecting from the shaft 15, and the collar 30 has a segmental clearance-recess 44 corresponding in angular extent to the door-opening movement of the shaft, as shown in Fig. 4. The positions of the parts here shown are those when the door 8 is closed and the handle 25 in its corresponding upright position. Obviously, the shaft 15 is free for the necessary door-opening movement in the direction of the arrow, while the handle 25 remains stationary. Or like movement 40 of the handle 25 will open the door, through engagement of the upper shoulder of the collar-recess 44 with the shaft key 43,—the piston 36 then moving idle in the cylinder 35, both of whose ends are vented except when pressure fluid is admitted to the upper end.
- 45 It will be seen that I have provided a door construction in which the frame 6 is in no way dependent upon bolts for holding it in position as has been customary in previous practice. On the contrary by my improvements the frame 6 is made 50 to overlap the inside edges of the door opening so that any outward pressure due to the escape of steam within the fire box only serves to force the frame 6 more tightly to its seat.
- I claim:—
- 60 1. Means for closing a doorway through a water leg of a locomotive fire box, including in combination, a door frame having an enlarged portion inside the box constructed and arranged to engage around the doorway opening so as to seat 65 itself against the inner wall of said water leg under pressure from within the box, a door opening inwardly into the box, and a seat on said frame for sustaining the door against outward pressure from within the box.
- 70 2. Means for closing a doorway through a water leg of a locomotive fire box, including in combination, a door frame having an enlarged portion inside the box constructed and arranged to engage around the doorway opening so as to seat 75 itself against the inner wall of said water leg

under pressure from within the box, a door mounted on said frame so as to open inwardly into the fire box and a seat on said frame for sustaining the door against outward pressure from within the box.

3. Means for closing a doorway through a water leg of a locomotive fire box, including in combination, a door frame having a portion adapted to line the opening through the water leg, said frame also being formed for endwise insertion through the opening and having an inner enlarged portion adapted to seat against the inner wall of said water leg when returned to normal position and retracted into the opening whereby it is sustained against outward pressure from within the box, a door mounted on said frame to open inwardly into the fire box, and a seat on said frame for sustaining the door against outward pressure from within the box.

4. The combination with a firebox doorway, of 20 a door frame engaged inside the firebox and extending outward into said doorway, and provided with a hinge-lug recess in its top; and an inward opening door provided with a hinge lug pivoted in said recess, said door closing outward 25 against said frame.

5. The combination with a firebox doorway, of 30 a door opening inward into the firebox, a door frame extending into the firebox and affording a seat for sustaining the door against outward pressure from within the firebox, and a door frame extension outside the firebox carrying the door operating mechanism.

6. The combination with a firebox doorway, of 35 a door frame engaged inside the firebox and extending outward through said doorway outside the firebox, and a supplemental frame outside the firebox around the outward extending portion of said first frame, which supplemental frame is secured to said first frame and to the firebox. 40

7. The combination with a firebox doorway, of 45 a door frame in the firebox, a door swingably mounted on said frame, a supplemental door frame outside the firebox, a door operating shaft rotatably mounted on the latter frame, and a link operating connection from said shaft to the door.

8. The combination with a firebox doorway, of 50 a door opening inward into the firebox and closing outward; a shaft with operating connection to the door; and means for operating said shaft including coacting clutch members thereon with inclined engagement surfaces, and spring means normally holding said clutch members engaged, but yielding to permit disengagement of the 55 clutch and independent movement of the shaft and door when the door is subjected to abnormal pressure from the firebox while in its open position.

9. Means for closing a doorway through a water leg of a locomotive fire box, including in combination, a door frame extending through the opening in the water leg with an inner enlargement adapted to seat against the inner wall of the water leg whereby it is sustained against outward pressure from within the box, and a supplemental frame outside the water leg secured to the outer portion of said first frame and adapted to seat against the outer wall of the said water leg whereby to sustain said first portion against movement into the fire box.

10. Means for closing a doorway through a water leg of a locomotive fire box, including in combination, a door frame extending through the opening in the water leg with an inner enlarge- 75

ment adapted to seat against the inner wall of the water leg whereby it is sustained against outward pressure from within the box, and a supplemental frame outside the water leg secured to the outer portion of said first frame and adapted to seat against the outer wall of said water leg

whereby to sustain said first portion against movement into the fire box, together with a door opening inwardly into the box and a seat on the inner frame against which said door is sustained against outward pressure from within the box. 5
